UNITED STATES PATENT OFFICE.

JOSEPH KOPCSAY, OF SOUTH BEND, INDIANA.

PROPELLER.

1,300,738.

specification of Letters Patent. Patented Apr. 15, 1919.

Application filed February 25, 1918. Serial No. 219,055.

To all whom it may concern:

Be it known that I, JOSEPH KOPCSAY, a citizen of the United States, residing at South Bend, in the county of St. Joseph and State of Indiana, have invented certain new and useful Improvements in Propellers, of which the following is a specification.

The invention relates to an improvement in propellers, and is adapted for various uses, such as driving machinery, in which case the propeller is driven by wind or water currents, and as a propeller for air or water craft, in which the propeller is power driven to act against the resistance of the air or water and thus drive the craft forward, as is well understood in the art.

The object of the invention resides in the provision of a propeller which, primarily, will produce a high torque ratio under the influence of a given wind or water pressure; and, secondarily, a propeller having blades of a form and angularity with respect to their common axis which results in most easily translating the wind or water pressure into rotary power.

A further object of the invention resides in the provision of a propeller of the character above set forth, which is of few parts and simple of structure, and hence easily and cheaply manufactured.

The invention in the preferred form of details will be described in the following specification, reference being had particularly to the accompanying drawings, in which:

Figure 1 is a side elevation of the propeller shown mounted on a shaft.

Fig. 2 is an end view thereof viewed in the direction of the work surfaces of the blades.

Fig. 3 is a perspective view thereof.

Referring now more particularly to the drawings, the reference numeral 5 designates a shaft upon which the propeller 6 is mounted, it being immaterial whether the shaft be driven by the propeller or the propeller by the shaft, according to the use to which the same is to be applied.

Primarily the propeller is adapted for use as a power producing element under the influence of wind or water pressure, and consists, preferably, of two blades 7 and 8, relatively inclined and oppositely disposed, forming substantially a right-angle when viewed edgewise of the blades, as shown in Fig. 1, with the apex of the angle directed forwardly. The forward edges of the

blades, as 9 and 10, are in alinement, and the blades extend at an angle and on opposite sides of a right line drawn transverse to their common axis, the angle of inclination of each blade with reference to the common axis being substantially forty-five degrees. The outer marginal edges 11 and 12 of the blades are curved so that, when viewed in plan, they would form arcs of the same circle, as will appear by considering Fig. 2 to be a plan view. In fact, however, due to the angle of inclination of the blades, the same are elongated and do not form a true quadrant of a circle, because due to such inclination the radial length of the inclined sides 13 would be considerably greater than the radial length of the edges 9 and 10, which are disposed at right angles with respect to the common axis of the blades.

In practice I prefer to form the entire propeller, with the exception of the blade faces, of a single casting. Thus I prefer to form the frame triangular in outline, the outer and inner hubs 14 and 15 being connected by radial aligned arms 16 extending from the hub 15, and inclined bars 17 extending from the hub 14 to the outer ends of the arms 16, said arms and bars being integrally formed with the hubs and with each other, the frame as a whole being strengthened by webs or ribs 18 extending lengthwise of the arms and bars. Extending outwardly from the outer hub 14 are bars 19, the outer ends of which are connected with the outer ends of the bars 17 by curved bars 20, thus forming an open frame to which the plane surface blades 7 and 8, which may be of sheet metal, fabric, or other suitable material, are secured in any suitable manner. As shown in Fig. 2, the blades of sheet metal may be fixed to the frame members by means of rivets 21, passed through the margin of the blades and the frame members.

By constructing the propeller with a skeleton frame and with spaced hubs, I obtain lightness of weight. The triangular formation of the frame also gives great strength, and by disposing the blades at substantially forty-five degrees of inclination to their common axis of rotation, and by the use of plane blades each presenting a large area of resistance to the propelling force, I have provided a very simple and easy running propeller translating a high percentage of the propelling force into rotary power.

What is claimed is:

1. A propeller comprising a frame, and plane inclined blades carried by and extending transverse the axis of the frame and in opposing relation, the forward edges of the blades being substantially alined and the faces thereof forming an approximate right angle.
2. A propeller comprising a triangular frame having its axis of rotation perpendicular with respect to its base and coincident with the apex thereof, and blades carried by the frame extending laterally thereof in opposing relation and inclined from the

apex to the base of the frame, at substantially right angles with relation to each other.

3. A propeller comprising an open triangular frame having spaced hubs alined perpendicular with respect to the base and coincident with the apex thereof, and blades carried by and extending transverse the frame in opposing relation and inclined at substantially right angles with relation to each other.

In testimony whereof I affix my signature.

JOSEPH KOPCSAY.
